UNITED STATES PATENT OFFICE

172,373

DRY CHEMICAL FIRE EXTINGUISHER

Franz Wagner, Chicago, Ill., assignor to Ansul Chemical Company, Marinette, Wis., a corporation of Wisconsin

Application December 1, 1953, Serial No. 27,859

Term of patent 14 years

(Cl. D16—2)

To all whom it may concern:

Be it known that I, Franz Wagner, a citizen of the United States, residing at 444 North Michigan Avenue, Chicago, Illinois, have invented a new, original, and ornamental Design for a Dry Chemical Fire Extinguisher, of which the following is a specification, reference being had to the accompanying drawing forming a part thereof, in which:

Figure 1 is a front view of the dry chemical fire extinguisher showing my new design,

Figure 2 is a right-hand side view thereof,

Figure 3 is a plan view thereof,
Figure 4 is a left-hand side view thereof, and
Figure 5 is a rear view thereof.

I claim:

The ornamental design for a dry chemical fire extinguisher, as shown.
